CHAIN SAW ATTACHMENT FOR TRACTORS

Chester A. Smith, Jr., Glendale, Oreg.

Application February 28, 1950, Serial No. 146,814

2 Claims. (Cl. 143—32)

This invention relates to a mobile power operated saw, and more particularly pertains to a chain saw especially well suited for sawing logs into sections, which is mounted to be supported and operated by tractors of the general type disclosed in the patents to Ferguson, Nos. 2,118,180 and 2,118,181.

The primary object of this invention is to enable a person to saw objects in a plurality of vertical planes without the necessity of moving the object and with a minimum expenditure of time, effort, and attention, and without requiring the use of expensive equipment other than a tractor that has other utility, or particular skill on the part of the operator.

Another important object of the present invention is to provide an attachment which may be efficaciously attached and removed from tractors of the well-known Ford-Ferguson type, which will be capable of realizing the foregoing object, which will be safe to operate, and which will itself be subject to a minimum possibility of damage during operation of the same.

Another important object of this invention is to provide an attachment of this character, in conformity with the foregoing objects, which will utilize the hydraulic lift of tractors of the aforementioned type for controlling the vertical movement of the sawing element of the attachment but in which a degree of freedom is permitted in the sawing element in the vertical plane so that the actual sawing operation will be automatic when once initiated, and which freedom will also afford a safeguard against damage to the sawing element upon striking obstructions during the sawing operations.

A further important object of the present invention is to provide an attachment of this character which will be adjustable to inclination to the horizontal plane, and which adjustability also permits the same to be compactly folded for storage, or for transport of the same upon a tractor when proceeding to the point of use.

A meritorious feature of the present invention resides in the simplicity of the means provided for mounting the attachment upon a tractor, which means are particularly well suited to cooperate with the implement lift means of Ferguson type tractors, and which renders the attachment the facility of attachment to the implement lift commensurate with the ease and flexibility with which agricultural implements are customarily attached to the lift of this type or character, and which requires no modification whatsoever of the tractor itself.

Another important feature of the present invention resides in the utilization of the lift arms of the tractor for vertical movement of the saw attachment, and the flexible connection between the lift arms and the attachment which permits independent upward movement of the attachment.

Still another important feature of the present invention resides in the foldability of the attachment and the angular adjustability between the chain saw and the drive therefor.

A final important feature of the present invention to be specifically enumerated herein resides in the simplicity of the attachment, which renders the same of great structural strength, durability and low manufacture and cost, and yet which is highly efficient for the purposes intended.

These, together with various ancillary features and objects of the invention which will later become apparent as the following description proceeds, are attained by the present invention, a preferred embodiment of which has been illustrated by way of example only in the accompanying drawings, wherein:

2

Figure 1 is a rear elevational view of the present invention showing the same attached to a tractor, and an alternate position of the attachment shown in dotted outline;

5 Figure 2 is a vertical sectional view of the present invention taken upon the plane of the section line 2—2 of Figure 1 and showing certain concealed portions thereof in dotted outline;

10 Figure 3 is a top plan view of the embodiment shown in Figure 1;

Figure 4 is a vertical sectional view taken upon the plane of the section line 4—4 of Figure 2; and

Figure 5 is a sectional detail view taken upon the plane of the broken section line 5—5 of Figure 1.

Reference is now made more specifically to the accompanying drawings, wherein like numerals designate similar parts throughout the various views, and in which the reference numeral 10 designates generally a tractor of the well-known Ferguson type which includes a transmission housing 12, axle housings 14 and 16, and hydraulically operated lift arms 18 that are pivotally mounted to the tractor 10 at 20 for movement about a transverse horizontal axis, which arms 18, as will be understood, are controlled in their position by an operator's control lever, not shown, carried by the tractor pin.

In mounting the subject matter of the present invention upon the tractor 10, the elevating links 21 remain secured to brackets 22 as on conventional Ford or Ferguson tractors, and it will be noted that the usual connecting links, not shown, between the lift arms 18 and the elevating links 21 have been removed.

The attachment, designated generally at 23, which constitutes the subject matter of the present invention, includes a triangular saw support frame 24, the horizontal portion 26 of which is connected by means of bolts 28 or lynch pins of the well known Ferguson type at the opposite ends thereof to the outer ends of the elevating links 21. The inclined portions of the frame 24 have their lower ends suitably secured to the opposite ends of the portion 26 and have their upper ends spaced to receive therebetween the outer end of a top link 32, and are pivotally connected by means of a bolt 34 extended through the portions 30 and the outer end of the links 32. As in the Ferguson type of tractor, an L-shaped bracket 36 has the outer end of one leg pivotally connected at 38 to the transmission housing 12 and the outer end of the other end pivotally and operatively connected at 40 to a spring assembly 42. A pair of such brackets 36 are provided and spaced to receive therebetween the inner end of the top link 32 and the inner ends of a pair of divergent members 44, the inner end of the links 32 and the inner ends of the members 44 being pivotally connected to the juncture of the legs of the brackets 36 by means of a pivot bolt 46 extending therethrough. The outer ends of the divergent members 44 are secured to the opposite ends of the portion 26 of the triangular frame 24 as well as the links 21 by means of the pins 28.

As best shown in Figure 2, the link 32 is formed in two sections that are connected at 48, the arrangement being such that a limited amount of vertical adjustment is permitted the triangular frame 24.

Mounted intermediate the ends of the portion 26 is a bearing 50 through which rotatably extends a shaft 52, one end of which is operatively connected to the power take-off 54 of the tractor 10 by means of an upwardly inclined intermediate shaft 56 and universal couplings 58, whereby the shaft 52 is rotated in response to rotation of the power take-off 54.

Pivotedly mounted upon the drive shaft 52 is a saw driving assembly 60 which includes a channel-shaped housing 62 and a member 64, which channel-shaped housing 62 is disposed to shelter therein a drive pulley 66 fixed upon the shaft 52 for rotation therewith. Formed at the end of the member 64 remote from the shaft 52 is a transverse housing 68 in which is journaled a shaft 70, to one end of which is keyed a driven pulley 72, and a pair of V-belts 74 are entrained over the pulleys 66 and 72 in the housing 60 for establishing a driving connection between the power take-off 54 and the pulley 72 through the shafts 32, universal couplings 58, shaft 52, and the pulleys 66 and 72. To the end of the shaft 70

opposite the pulley 72 is mounted the driven sprocket 76 of the chain saw assembly indicated at 78.

The chain saw assembly 78 includes a frame 80 and the saw chain 82 which is entrained over the sprocket 76. Since the chain saw assembly 78 does not, in itself, constitute the subject matter of the present invention and is entirely conventional in design, it is believed that a further explanation of the same is not necessary.

Except as hereinafter pointed out, the connection between the drive assembly 60 and the chain saw assembly 78 is analogous in all fundamental respects to that shown in the patent to Arsneau, issued May 9, 1944, No. 2,348,588, which includes means indicated at 84 for adjustably extending the frame 80 for tensioning the chain 82 and in which the frame 80 includes a sleeve 86 rotatably mounted on the housing 68. As will be described hereinafter, the assembly 60 is adjustably retained in fixed angular relationship with the assembly 78.

In order to pivotally move the assembly 60 and assembly 78 in a vertical plane about the axis of the shaft 52, a laterally extending lever 88 is suitably secured to the assembly 60, and the outer end of the lever 88 is operatively connected to one of the lift arms 18 by means of a chain 90. One end of the chain 90 is secured, as at 92, to the bifurcated outer end of the arm 18 and is secured at its other end to the outer end of the lever 88 and is intermediately entrained over a guide pulley 94 carried by a bracket 96, which bracket is, in turn, secured to the portion 26 at the end remote from the chain saw assembly 78 as best shown in Figures 3 and 4, the arrangement being such that upon upward movement of the arm 18 the assemblies 60 and 78 are moved from the full line position shown in Figure 1 to the alternative raised position shown in dotted outline at 98.

In order to adjustably fix the angular relationship between the assemblies 60 and 78, a bracket arm 100 connects the member 64 and the frame 80, as best shown in Figures 1 and 3. In the preferred construction, the bracket 100 is secured as at 102 to the frame 80 and is adjustably secured at its other end to a plurality of projecting lugs 104 angularly disposed on the housing 68, whereby, as will be readily understood, the angular relationship between the assemblies 60 and 78 may be adjustably fixed.

In order to prevent side sway of the attachment, a stabilizing brace 106 is secured at its inner end to the axle housing 14 and at its outer end to the end of the portion 26 adjacent the chain saw.

The operation of the attachment will be readily understood. One of the most important advantages of the present invention resides in the fact that the operator may sever a log or the like into a plurality of sections without leaving the operator's position of the tractor, and another important advantage of the present invention resides in the flexible connection between the lift arm 18 and the attachment 23, whereby the attachment 22 may be positively lifted while the chain saw 78 advances into a log by gravity, with the flexible connection serving only to limit the rate of advance as desired.

Since, from the foregoing, the construction and advantages of this invention are readily apparent, further description is believed to be unnecessary.

However, since numerous modifications and equivalents will readily occur to those skilled in the art after a consideration of the foregoing specification and accompany-

ing drawings, it is not intended to limit the invention to the exact embodiment shown and described, but all suitable modifications and equivalents may be resorted to which fall within the scope of the appended claims.

Having described the invention, what is claimed as new is:

1. A saw attachment for mounting a saw on a tractor of the type having hydraulic lifting arms, a power take-off, a transverse drawbar secured to the tractor frame by a pair of elevator links and supported by a pair of divergent members secured adjacent the ends of said drawbar and to a bracket mounted on the tractor, said attachment comprising a pair of downwardly divergent frame elements connected together at their upper ends, the lower ends of said divergent members being secured to said drawbar, an articulated link secured between the upper end of the divergent members and said bracket, a bearing mounted intermediate the ends of said drawbar, a shaft journaled in said bearing, a driving connection between said shaft and said power take-off, a housing journaled on said shaft, a sheave fixed on said shaft within said housing, a transverse shaft journaled in said housing, a sheave on said transverse shaft in said housing, a flexible driving element entrained over said sheave, a saw operatively connected to said transverse shaft.

2. A saw attachment for mounting a saw on a tractor of the type having hydraulic lifting arms, a power take-off, a transverse drawbar secured to the tractor frame by a pair of elevator links and supported by a pair of divergent members secured adjacent the ends of said drawbar and to a bracket mounted on the tractor, said attachment comprising a pair of downwardly divergent frame elements connected together at their upper ends, the lower ends of said divergent members being secured to said drawbar, an articulated link secured between the upper end of the divergent members and said bracket, a bearing mounted intermediate the ends of said drawbar, a shaft journaled in said bearing, a driving connection between said shaft and said power take-off, a housing journaled on said shaft, a sheave fixed on said shaft within said housing, a transverse shaft journaled in said housing, a sheave on said transverse shaft in said housing, a flexible driving element entrained over said sheave, a saw operatively connected to said transverse shaft, an adjusting lever secured on said housing adjacent said bearing, a sheave journaled adjacent the end of said drawbar, a flexible tension member secured to said lifting arm and to said lever, said tension member being entrained over the sheave adjacent the end of said drawbar.
